CLAIM

The ornamental design for a voltage regulator as shown and described.

DESCRIPTION

FIG. 1 is a front, left and top perspective view of a voltage regulator showing my new design;

FIG. 2 is a rear, right and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of encircled portion 9 of FIG. 1; and,

FIG. 10 is an enlarged view of encircled portion 10 of FIG. 2.

The broken lines depict portions of the voltage regulator that form no part of the claimed design.

1 Claim, 10 Drawing Sheets
